UNITED STATES PATENT OFFICE.

JOHN A. KRAMER, OF WINIGAN, MISSOURI.

HARNESS-PAD FORMER.

SPECIFICATION forming part of Letters Patent No. 662,123, dated November 20, 1900.

Application filed February 15, 1900. Serial No. 5,361. (No model.)

To all whom it may concern:

Be it known that I, JOHN A. KRAMER, a citizen of the United States, residing at Winigan, in the county of Sullivan and State of Missouri, have invented certain new and useful Improvements in Harness-Pad Formers; and I do hereby declare the following to be a full, clear, and exact description of the invention, such as will enable others skilled in the art to which it appertains to make and use the same.

This invention relates to saddlery appliances, and more particularly to forming means for use in the construction of pads for harness-saddles, whereby it is feasible to have the upper and the lower parts of the cover formed each of a single piece, the two pieces being tacked together at their longitudinal edges, thereby greatly simplifying and cheapening the construction and enabling a workman to turn out a greater number of pads in a given time than possible by the method generally practiced.

The invention also enables the neck portion of the pad to be formed so as to yield, which is essential to adapt the pad to harness of different girth and be free from wrinkle or crease.

The invention consists, essentially, of a shaper comprising a thin metallic plate for 30 clenching the points of the tacks or fastenings and laminated forming-blocks detachably fitted to the end portions of the clencher-plate.

The invention also consists of the novel 35 features, details of construction, and combination of the parts, which hereinafter will be more fully disclosed and finally claimed, and for this purpose and also to acquire a knowledge of the merits of the invention and the 40 structural details whereby the results are attained reference is to be had to the appended description and the drawings hereto attached.

While the essential and characteristic features of the invention are necessarily susceptible of modification, still the preferred embodiment of the invention is illustrated in the accompanying drawings, in which—

Figure 1 is a rear view of a harness-saddle 50 of ordinary construction supplied with a pad constructed in accordance with the principles of this invention. Fig. 2 is a perspec-

tive view of the pad. Fig. 3 is a detail perspective view showing the manner of constructing a cover or casing. Fig. 4 is a longitudinal sectional view of the shaper.

Corresponding and like parts are referred to in the following description and indicated in all the views of the drawings by the same reference characters.

The saddle illustrated in Fig. 1 may be of any of the forms commonly employed in connection with single or double harness and is illustrated to demonstrate the application of the invention, which latter deals more particularly with the instrumentalities for use in the construction and manufacture of the pad forming a lining to the saddle, the latter having the usual trimmings for the skirts, girth, overdraw, reins, and back-strap.

The pad (shown most clearly in Fig. 2) has its cover or casing formed of two parts—the upper covering 1 and the lower covering 2—the two parts being secured at their longitudinal edges and ends by means of tacks 3 or 75 like fastenings capable of having their points clenched. The parts 1 and 2 of the cover or casing are each formed of a single piece which are stitched together at an intermediate point, as shown at 4, to form the neck or flexible portion, which enables the end portions of the pad to adapt themselves to the girth of the animal.

The means for giving the required form to the cover or casing consist of a metallic plate 85 5 of requisite length and width and thinness, said plate being preferably of steel, so as to turn the points of the fastenings 3, and properly designated as a "clencher-plate." Forming-blocks are detachably fitted to the under side of the end portions of the clencher-plate 5 and involve a laminated structure, each being composed of a series of plates 6, 7, and 8, disposed the one upon the other and tapering in length, their thicker ends being 95 beveled to conform to the inner ends of the end portions of the pad. As is well known, the inner ends of the side members of harness-pads are made thick to conform to the space at each side of the backbone, and in order to 100 give the proper shape to the pad the inner ends of the plates 6, 7, and 8 are made thick and taper to an edge at their outer ends. By having the forming-blocks composed of a

plurality of sections or plates the latter can be readily removed after the cover or casing has been formed, the plates or sections being withdrawn one at a time through the open 5 end of the cover. These plates or sections 6, 7, and 8 may be of wood, metal, or other material, so long as they are sufficiently stout to withstand the strain incident to stretching the parts of the cover thereover in the formation 10 of the casing. A series of thumb-screws 9 connect the plates 6, 7, and 8 with the end portions of the clencher-plate, and jam-nuts 10 are mounted upon said thumb-screws to hold the upper part 1 of the cover or casing 15 in position when placed upon the clencher-plate in the initial step of forming the casing. The top portion 1 of the cover may consist of any number of plies, and the burs and terrets and other fastenings are secured 20 thereto in any desired manner.

After the parts of the shaper are assembled and the top portion 1 of the cover has been placed in position upon the clencher-plate the lower part 2 of the cover is secured at one 25 edge to an edge portion of the part 1 by means of tacks 3 or like fastenings, the latter being driven through the overlapping edge portions of the parts 1 and 2 and their points being clenched by coming in contact with the plate 30 5. The free edge portion of the part 2 is drawn about the opposite edge of the shaper by means of pliers or other convenient means, and said edge is secured to the opposite edge portion of the part 1 by tacks 3 or similar fastenings, the points of the latter being inturned and clenched by coming in contact with the plate 35 5. After the edge portions of the parts 1 and 2 have been secured the jam-nuts 10 are loosened and the thumb-screws 9 removed, 40 after which the clencher-plate is withdrawn from the cover or casing through an open end, when the parts 1 and 2 are transversely stitched at an intermediate point, as shown at 4, so as to form a neck or flexible part intermediate the ends of the pad. The forming-blocks 45 are now removed through the open ends of the cover or casing by withdrawing the sections or plates therefrom one at a time.

The casing is now in condition to be stuffed with any suitable filling, which is packed into 50 the cover through the open ends. After the cover or casing has been stuffed the end portions of the lower part 2 of the cover are folded over the terminal portions of the part 1 and secured to the latter by tacks or like 55 fastenings 3, as shown most clearly in Fig. 2. The pad is now complete and ready for use in connection with a saddle of any desired make.

Having thus described the invention, what 60 is claimed as new is—

1. A harness-pad shaper, comprising a clencher-plate having terminal forming portions detachably fitted thereto, whereby the pad may be formed preliminary to its introduction into a mold for stuffing, substantially 65 as described.

2. A harness-pad shaper, comprising a clencher-plate, forming-blocks coöperating with the end portions thereof, and fastening devices detachably connecting said forming-blocks with the clencher-plate, substantially 70 as described.

3. A harness-pad shaper, comprising a comparatively long, narrow and thin clencher- 75 plate, laminated forming-blocks, clamp-screws passing through openings in the clencher-plate and detachably connecting the forming-blocks to the end portions thereof, and jam-nuts mounted upon the clamp-screws 80 to secure the top part of the pad-cover to the clencher-plate, substantially as described.

4. A harness-pad shaper, comprising a clencher-plate, terminal forming devices upon the under side of said plate, and means for 85 detachably connecting the forming devices to the clencher-plate and also clamping the top part of the pad-cover down upon the upper surface of said plate, substantially as set forth.

In testimony whereof I affix my signature in presence of two witnesses:

JOHN A. KRAMER. [L. S.]
